PHOTOPRINTING DEVICE

Josef Horn, Wiesbaden-Biebrich, Germany;
vested in the Alien Property CustodianApplication March 6, 1941, Serial No. 381,999
In Germany February 26, 1940

6 Claims. (Cl. 95—73)

Photoprinting devices are already known in which a luminescent tube connected with a reflector is passed along a glass plate serving for placing the copying material thereon. The luminescent tube extends in that case perpendicularly to its direction of motion all over the glass plate so that the copying material may be uniformly illuminated.

The present invention relates to a photoprinting device of the afore-described kind in which a mercury vapor high-pressure tube is used as a source of light. A considerable evolution of heat of the mercury vapor tube becomes inconvenient insofar as the glass plate serving for placing the copying material thereon, is strongly heated; this may have a detrimental action on the copying material which in most cases is very sensitive to heat. By causing, as is known by photoprinting devices of other kinds, a current of cooling air to pass between glass plate and mercury vapor tube, the glass plate, it is true, is effectively cooled. At the same time, however, a strong cooling of the mercury vapor tube takes place, this being very detrimental. As is known, the emission of light of said tube considerably decreases when it is cooled. The device in question is provided, according to the present invention, with a cooling apparatus of a special kind by which it is possible to avoid the afore-named drawbacks.

According to the present invention nozzles are provided in a photoprinting device of the kind herein described. Said nozzles are connected with a suction pipe or a compressed air piping. They are situated near the glass plate along the two edges of the reflector which are parallel to the axis of the lamp. The apertures of the nozzles are directed towards the glass plate. Moreover, it is necessary that the nozzles situated at both sides of the reflector are arranged in about the same distance from the source of light. It is suitable to provide on each side of the reflector a slot nozzle extending all over the length of the reflector. It is, however, also possible to subdivide each of the two long slot nozzles into a row of short nozzles. The nozzles are connected according to the invention with the system consisting of luminescent tube and reflector so that they move together with said system. The glass plate serving for placing the printing material may be cooled by means of the cooling device herein described and the source of light is not affected by the cooling air.

It may be advisable to mount the nozzles closely to the longitudinal edges of the reflector. By

such a mode of arrangement any cooling of the luminescent tube is most safely avoided. A construction has been found to be the most advantageous according to which two nozzles are formed at both sides of the luminescent tube by the edges of the reflector and the edges of a casing surrounding the reflector. Care is thus taken that the reflector, tool, is cooled by the current of air produced, whereby the heat produced within the glass plate is indirectly also reduced. According to the mode of construction in question of the device of the present invention a suction piping is introduced centrally into the chamber formed by the reflector and the casing named above. The chamber is closed with the exception of the apertures of the two nozzles. By an arrangement of said kind the suction at both nozzles is uniformly strong. It is also possible to operate with compressed air, but this mode is less advisable. By applying suction air it is possible by a simpler way to lead into the atmosphere the cooling air after it has been heated. A suitable method of eliminating the cooling air is extremely advisable owing to its high content of ozone.

The new kind of cooling is, of course, also suitable if instead of the mercury vapor high pressure tube there is used another source of light evolving much heat but being sensitive to cooling.

According to the invention the suction pipe or pressure pipe of the cooling device connected with the source of light is preferably introduced into an aperture of a band extending along the path of motion of the suction piping. By said band the open part of a canal is closed; said canal also extends along the path of motion of the suction pipe or pressure pipe and in its interior is in connection with a pump, a ventilator or the like. The aforesaid band is displaceable above the open part of the canal, while maintaining its packing effect.

The device according to the present invention is diagrammatically illustrated, by way of example, in the accompanying drawings.

Fig. 1 is a longitudinal section on line 1—1 of Fig. 2.

Fig. 2 is a plan of the device, the copying frame being removed.

Fig. 3 is a section through the reflector and the casing on line 3—3 of Fig. 2, the connection piece 33 being omitted and

Fig. 4 is a section through the suction canal on line 4—4 of Fig. 1.

The device consists of a wooden frame 1 into

which a glass plate 2 has been inserted. Above said glass plate a lid 4 provided with a rubber joint 3 is mounted. By means of said lid it is possible to press the original and the photographic printing paper to the glass plate. Below the glass plate a casing 5 is mounted which has the form of an elongated trough and is connected with rollers 8 sliding in rails 7. The casing is moved to and fro with a defined velocity below the glass plate, and it is driven by an electro-motor 9 which is built together with a reduction gear 9. The chain wheel 10 is situated on the driving journal of the gear and causes by way of chain 11 and chain wheel 12 the shaft 13 to move. The latter is carried on the bearings 14. The chain wheels 18 as well as the chain wheels 19 being on the same axis with the chain wheels 16 are driven by way of the chains 15 which are guided on the chain wheels 16 at the ends of shaft 13. The two chains 17 are driven with constant velocity by the chain wheels 18. The axles of the chain wheels 18 and 19 are carried on the bearings 19. Chain wheels 17 the axles of which are carried on the bearings 19 also serve for guiding the chains besides chain wheels 18. A haulage bolt 20 revolving with the chain is mounted at each of the two chains. The two bolts 20 are engaged in driving arms 21 which are mounted to the casing 5 and are provided with a slot wherein the bolts 20 may vertically move up and down. By the afore-named connection the casing is taken along with the chains 17 and moves to and fro below the glass plate 2 when the chains are rotating. The casing 5 is subdivided into three divisions by two partitions 22. The reflector 23 is situated in the central part and is mounted at the partitions 22 so that two nozzles 24 are formed by its upper edges and the casing 5. The space between the reflector 23 and the casing 5 is connected with the suction piping 25. The mercury vapor high-pressure tube 26 is arranged in the focus of the reflector 23 and is mounted in the partitions 22 so that the two heads 27 which are particularly sensitive to the action of cold are situated in the outer parts of the casing 5. The edges of the reflector 23 are curved in such a manner that the central portion of the nozzles 24 formed by said edges of the reflector and those of the casing 5 is narrower than the two outer portions. By the construction as herein described the cooling air is caused to flow uniformly all over the length of the nozzles and care is thus taken that the entire copying surface is uniformly cooled. Below the path of motion of the suction pipe 25 there is mounted a canal 29 of rectangular section which extends along the entire path of motion of the suction pipe. The canal is open towards the top part. The aperture is closed in an air-tight manner by an endless band 30 which is passed over the rollers 31. Metal rods 32 may serve for stiffening the band to which they are fastened and extend all over the breadth of the band. The bottom part of the suction pipe 25 is joined to a branch 33 which is fastened to the endless band 30; there is thus attained a connection between the suction pipe 25 and the interior of the canal 29, which is connected by the band 34 with the suction branch of the ventilator 28. The air is led into the atmosphere through the pressure tube 35 by means of the ventilator.

The course of the cooling air is illustrated by arrows in Fig. 3 of the drawings. The air passes from outside over the edges of casing 5 into the nozzle 24 formed by the reflector 23 and the cas-

ing 5; it flows along the glass plate 2 whereby said plate is cooled. The two currents of air are then passed between reflector 23 and casing 5, are collected in the bottom part of the space formed by the reflector and the casing and are removed by the suction pipe 25.

During the copying process the casing 5 together with the lamp 26 is moved to and fro below the glass plate. Since the suction pipe 25 is joined to the branch 33 which is fastened at the band, the band 30 also moves to and fro over the canal 29. By this method of operating the ventilator 28 in motion is permanently in connection with the inner space formed by reflector 23 and casing 5 and air is permanently sucked in by the nozzles 24. The air sucked up by ventilator 28 by way of tube 34 is removed by the pressure piping 35 and must as a rule be entirely led into the atmosphere owing to its ozone content.

I claim:

1. In a device of the kind described a glass plate serving for placing the copying material thereon, rails extending along said glass plate, a casing between said glass plate and said rails extending perpendicularly to the direction of said rails over said glass plate, having the form of an elongated trough directed with its concave side towards said glass plate and being provided with rollers guided by said rails, a reflector arranged in said casing and being so constructed that two slot nozzles extending over said glass plate are formed by means of the longitudinal edges of said casing and the edges of said reflector, a mercury vapor high-pressure tube arranged in the focus of said reflector, a driving device serving for moving the system consisting of said casing, said reflector and said tube to and fro along said glass plate, a pipe fitting centrally into the space between said reflector and said casing, a canal the interior of which is connected with a suction device arranged beneath said casing and the said rails, extending along the path of motion of said casing and being open on the side directed towards said casing and a band above the open side of said canal forming a displaceable closure of said canal, the said pipe fitting into an aperture of said band.

2. In a photoprinting apparatus, a glass plate serving for placing the copying material thereon, a luminescent lamp in the form of a tube evolving much heat but being sensitive to cooling near said glass plate and extending along said glass plate, a reflector surrounding said lamp so as to concentrate the light of the lamp on said glass plate, a casing surrounding said reflector in such a manner that the edges of the reflector and the edges of said casing form nozzles near said glass plate, which nozzles are directed towards said glass plate, the said lamp, reflector and casing being rigidly connected with one another, an airing device joined with the space between said reflector and said casing and means for moving the said system consisting of said lamp, reflector and casing to and fro along said glass plate perpendicularly to the axis of said lamp.

3. In a photoprinting apparatus as claimed in claim 2, a mercury vapor high-pressure tube as luminescent lamp.

4. In a photoprinting apparatus, a glass plate serving for placing the copying material thereon, a mercury vapor high-pressure tube near said glass plate and extending along said glass plate, a reflector surrounding said tube so as to concentrate the light of the tube on said glass plate.

a casing surrounding said reflector in such a manner that the edges of the reflector and the edges of said casing form two slot-nozzles parallel to the axis of said tube, which nozzles are directed with their apertures towards said glass plate, a pipe joined with the space between said reflector and said casing which pipe is joined with a suction device, said tube, said reflector, and said casing being rigidly connected with one another, and means for moving said system consisting of 5 said tube, reflector and casing to and fro along

said glass plate perpendicularly to the axis of said tube.

5. In an apparatus as claimed in claim 4, rails extending along the path of motion of said system consisting of said tube, said reflector, and said casing, rollers fastened to said casing, which rollers are guided by said rails.

6. A device as claimed in claim 4, wherein said pipe fits centrally into said space between said reflector and said casing.

JOSEF HORN.
